UNITED STATES PATENT OFFICE.

THOMAS F. PAYNE, OF PITTSBURGH, PENNSYLVANIA.

FLUSH VALVE.

Application filed November 10, 1923. Serial No. 673,947.

This invention is for an improvement in flushing valves for water closets, particularly those utilizing a jet for ejecting the contents from the bowl.

In present types of sanitary bowls, flushing is generally effected from local tanks designed to give a relatively large flow of water in a short time, or water is supplied from pipes of relatively large diameter, in which comparatively high pressures are maintained. The present invention proposes to provide means for flushing a bowl capable of use with small sizes of pipes and without the use of tanks and without requiring unusually high pressures.

The important feature of the present invention is the combination with a bowl designed to give the desired distribution of water, of a valve for cooperation therewith to supply the water to the separate points of distribution in proper sequences and in the desired time relation, to properly flush the bowl, for effecting the desired flow of water through the different channels of the bowl at the proper intervals of time.

Another important object of the invention is to provide a valve for this purpose, which shall be relatively simple and sturdy, which is easy to manufacture and capable of withstanding hard usage.

An additional feature of very great importance resides in the assembly of distributing and timing valve elements on an operating means in such manner that the parts may have slight relative movements, whereby they may adjust themselves to irregularities in the casing in which they move, whereby such careful machining of the parts to such a degree of accuracy as to preclude commercial practicability is avoided.

These and other objects and advantages are attained by my invention which is illustrated in the accompanying drawings.

In the drawings:

Fig. 1 is a vertical section through the valve and the receiving pocket of the bowl, showing the manner of attaching the valve to the bowl, and showing the valve in closed position;

Fig. 2 is a side view of the valve on a smaller scale, showing it removed from the bowl;

Fig. 3 is a view similar to Fig. 1, showing the position of parts with the valve stem depressed to its fullest extent;

Fig. 4 is a view partly in vertical section

and partly in elevation, showing the sliding valve member;

Fig. 5 is a bottom view of the valve member shown in Fig. 4; and

Figs. 6, 7 and 8 are diagrammatic views indicating the different positions of the distributing valve.

My improved valve is adapted to be used in connection with a water-closet bowl of suitable construction, in the general manner shown in the patent of Scott No. 796,458.

Projecting laterally from one side of the bowl A is a valve receiving pocket 16 which is formed integrally with the bowl. The pocket has an upper flange 17, an intermediate flange 18, and a lower flange or edge 19. Chamber 15 is disposed between upper flange 17 and intermediate flange 18. A second chamber 20 is formed between flange 18 and bottom 19, and this chamber opens into a side passage 21 leading down the side of the bowl and under the bottom thereof to the ejector jet 22 at the lowermost end of passage 10.

When water is introduced into the bowl from the rim, the water circles around in the upper part of the bowl, tending to form a swirl, to the center of which the contents of the bowl are carried.

When the swirling action has been continued a proper length of time, the water to the rim is shut off, and the full pressure of water directed up into the upleg through jet 22, it will be seen that all contents brought below the inverted dam will be ejected or forced through the up-leg of the closet.

After the stream of water has been forced through the jet a sufficient time, water may again be supplied to the rim, the water flowing out both the rim and the jet, to restore the normal water level in the bowl.

The valve is designed to effect the distribution of the water in the manner outlined.

The valve includes a metal casing or body 25 having a removable cap 26 threaded into its lower end and a removable cap 27 screwed onto its upper end. Formed on the outside of the upper part of the body, which is generally cylindrical, are a plurality of ribs 28 which have threaded surfaces 29 to engage a flanged nut 30. At 31 is an upper port in the casing, and at 32 is a lower port. The ribs 28 form bridges to join the different sections of the casing after ports 31 and 32 are formed. These ports may be formed by setting the casing up in a lathe and cutting

annular grooves in the casing with an inside cutting tool, until the wall of the casing has been entirely cut away, leaving the sections connected by the ribs. This arrangement lends itself to cheap manufacture, and provides annular ports in the casing of sufficient size to pass the necessary amount of water. Below the lowermost port 32 is a lateral flange 33. Below the plane of this flange is a water inlet connection 34.

The flange thus divides the casing into upper and lower parts, the chamber 35 within the upper part, in which are ports 31 and 32, being called the valve or distributing chamber, and the chamber 36 in the lower part being termed the timing chamber. A transverse partition 37 inside the casing, between the two chambers and above the water inlet connection, definitely separates the two chambers. This partition has a central opening 38 therein, around which, on the under face of the partition, is a valve seat 39.

23 The upper cap 27 has a packing gland 40 centrally disposed thereon, through which an operating rod 41 passes. The upper end of the rod is threaded and screwed thereto is a knob 42. The knob has a downwardly projecting extension 43 which, when rod 41 is moved downwardly, contacts with nut 40^a of the gland to limit the downward movement of the rod. In order to adjust the distance, the rod may be moved, the knob 35 may be screwed up and down on the rod, a set screw 44 being provided to hold the knob in adjusted position.

40 The lower end of rod 41 has a rectangular head 45 thereon which is received in a transversely extending rabbeted slot 46 in a connecting member or nut 47, this nut having a central threaded opening 48 to receive the upper threaded end of a rod 49. The head 45 has a slight clearance in the slot 46.

45 Below the nut 47 is a spacing ring 50 and on the shaft 49, below the spacing ring, is a flange or washer 51.

In the chamber 35 is a slidable sleeve valve 52 which is somewhat like an inverted cup in shape, the valve being hollow, but having a perforated spider 52^a at its top, a bottom plan view of the spider being shown in Fig. 7. The opening in the spider permits water to pass therethrough. The spider 55 has a central opening 52^b through which rod 49 passes, spacer 50 being disposed in this opening. The valve is thus loosely secured to the composite stem 41-49, the spider being confined between nut 47 and washer 51.

60 Because of the fact that rod 41 passes through a packing and, therefore, must move in a straight line, the loose coupling at 45-46 between the rod 41 and rod 49 is provided, so that the lower rod section may 65 adjust itself to inaccuracies due to imperfect

machining or fitting of parts, without causing rod 41 to bind. If the stem 41-49 were a single rigid structure, machining of parts would have to be so accurate as to render its manufacture by ordinary methods impractical. For the same reason, a slight play is allowed between the valve and the stem, as described.

The distributing sleeve valve 52, which is, of course, cylindrical in shape, has ribs 53 on its interior for connecting the parts after an annular port 54 is cut in the periphery of the valve, as best illustrated in Fig. 6. This port 54 is substantially midway between the ends of the valve, dividing the valve into upper part 52' and lower part 52''. The annular port 54 normally registers with upper port 31 in the casing, as shown in Fig. 3, and the lower end of the valve is well above the lower port 32.

Rod 49 extends down through opening 38 and its extreme lower end is threaded and screwed into a metal core 55 in the timing chamber 36. Above its lower threaded end, the rod 49 is fluted for a short distance, as indicated at 56, and spaced upwardly from the fluted portion is a flange 57. Confined between member 55, which has a flange 55^a at its upper end, and a washer 58 on rod 49, is a valve member 59.

This valve member is received within a central chamber 60 of a reciprocable valve member 61. This valve member has an extension 62 on the upper end thereof which has a well 63 therein and is exteriorly threaded. The top of the extension has saw cuts 64 therein. Around the base of the extension is a valve ring 65 held in place by nut 66 on the exterior of the extension. This valve ring is normally held against seat 39 to prevent water entering inlet 34 from passing up into valve chamber 35.

The fluted part 56 of rod 49 passes through an opening in the bottom of well 63, and at 67 is a seat for cooperation with valve 59.

In the well 63, around the rod 49 and confined between the bottom of the well and the flange 57, is a compression spring 68 for urging valve 59 against seat 67.

The valve 61, for convenience of construction and to reduce the amount of metal required for it, has an annular channel 69 therein. In the valve body is a passage 70 for establishing communication between the upper and lower ends of the valve on the timing chamber. This passage is restricted by a valve member or sliding pin 71 urged downwardly by a compression spring 22. It is at all times sufficiently loose to provide for a slight leakage around it.

At 73 is a compression spring for urging member 55 and the valve 61 and the various parts connected therewith upwardly to closed position.

The valve B is put into the pocket in the bowl by inserting it through the bottom of the pocket. As the bowls are manufactured from clay, different bowls are not the same and each one will have irregularities different from others. A soft rubber gasket 75 is accordingly placed on nut 30 and a second one 76 on flange 33. Nut 30 is adjusted by fitting the valve into the pocket, determining the proper position for the nut, removing the valve, and setting the nut. Nut 30 may thus be set so as to bring gaskets 75 and 76 against the flanges 18 and 19, respectively, to be forced into sealing engagement therewith. 15 A gasket 77 is then placed on flange 17.

During the fitting of the valve, knob 42 and cap 27 are removed. Cap 27 is then applied, and screwed down, compressing gasket 77 and lifting the valve body, thereby compressing gaskets 75 and 76. Thus, the valve is quickly fitted to the bowl. When so fitted, port 31 opens into chamber 15 and port 32 opens into chamber 20.

Before knob 42 is applied, a porcelain hood 78 may be fitted over the pocket and valve, this hood having a metal bushing 79 clamped therein to guide the knob. The knob may then be applied and screw 44 is set. Because of the head 45 being rectangular, rod 41 is held against turning with the knob as the knob is screwed down.

The parts of the valve are normally in the position shown in Fig. 1. The inlet water pressure communicates to the lower end of the valve body 61 through passage 70, so that the inlet pressure and spring 73 both tend to hold ring 65 against seat 39.

When knob 42 is forced down, flange 57 first moves down against the end of extension 62, unseating valve 39, allowing the water in the timing chamber 36 to escape up into the well around the fluted portion 56 of the stem, and breaking the resisting pressure of this water. This immediately establishes a differential pressure between the inlet water and the water in the lower end of the timing chamber, as water will not flow as rapidly through passage 70 as it escapes into the well.

As soon as valve 59 opens, and the differential pressure is established, the plunger may be easily forced further down, unseating valve 65. The area of valve member 61 exposed to inlet pressure downwardly is then greater than the area subject to upward pressure, and the plunger will be assisted in its downward movement by the water pressure. Consequently, the plunger, as the entire reciprocable assembly may be termed, may be easily forced downwardly by a single application of pressure in a very short period of time. The downward movement will be limited by the knob, as hereinbefore described.

When the knob is forced down to its lowermost extent, distributing valve 52 is moved

a corresponding distance. Port 32 is covered by surface 52" of the valve 52, while port 31 is uncovered. Water coming into pipe 34 passes through opening 38 and up through the top of the valve and out port 31 70 into chamber 15, as illustrated by the arrows in Fig. 8.

As the water continues to run, spring 68 closes valve 59 and a water pressure begins to build up in the lower end of the timing chamber, water entering through passage 70. This, with the assistance of spring 73, forces valve 61 and valve 52 upwardly until port 32 is uncovered and port 31 is covered by area 52' of valve 52. Then all the water 80 flows into chamber 20. The position of the parts is shown in diagram in Fig. 7.

Finally, port 54 in valve 52 comes into register with port 31, and the flow of water is divided until valve 61 is again moved up 85 to closed position. As port 31 is wider than port 54, the time interval between the time when port 54 first registers with port 31 and the valve 61 has finally closed will be appreciable, and for a short duration of time, water will flow through both ports 31 and 32, as indicated in Fig. 8.

Thus, it will be seen that the valve will first supply water to the rim of bowl A, then to the jet, and then to both the rim and the jet. By concentrating the entire flow first into the rim and then into the jet, greater efficiency is obtained with less water and smaller supply pipes may thus be used, than with any present type of flushing valves. 100 Neither need the water pressure be very great to effectively flush the bowl.

Where the water is supplied at very high pressures, it is desirable that the valve close more quickly than when the water is at low 105 pressure. Proper adjustment may accordingly be made by adjusting knob 42 to allow for a shorter movement of the parts when the pressure is high and a greater movement when the pressure is low.

Pin 71 is made of sufficient length to engage the shoulder 26^a in the bottom of the cap 26, so that when the valve 61 moves down, the movement of the pin will be limited, and a relative movement between the pin and the valve may be effected. This tends to keep the restricted passage around the pin from becoming clogged with solid particles.

I claim as my invention:

1. A valve for flushing water closets comprising a casing, a valved passage between opposite ends of the casing dividing the casing into a timing chamber and a valve chamber, a valve for controlling communication between the two chambers, said valve including a plunger having a restricted passage therethrough and having a normally closed by-pass therethrough, a rod having a limited movement relatively to the plunger,

- er for moving the plunger to open position, a valve on the rod in said by-pass for opening the by-pass when the rod is first moved relatively to the plunger, means for urging the 5 plunger to closed position, outlet ports in the valve chamber, a sleeve in the valve chamber movable with the rod having an annular port for controlling the passage of water through the outlet ports, and a water inlet passage 10 opening into the timing chamber end of the casing.
2. A valve for flushing water closets comprising a casing, a valved passage between opposite ends of the casing dividing the casing into a timing chamber and a valve chamber, a valve for controlling communication between the two chambers, said valve including a plunger having a restricted passage therethrough and having a normally 15 closed by-pass therethrough, a rod having a limited movement relatively to the plunger for moving the plunger to open position, a valve on the rod in said by-pass for opening the by-pass when the rod is first moved relatively to the plunger, means for resiliently 20 urging the rod into the by-pass valve closing position, means for urging the plunger to closed position, outlet ports in the valve chamber, a sleeve in the valve chamber movable with the rod having an annular port for controlling the passage of water through the outlet ports, and a water inlet passage opening into the timing chamber end of the casing.
3. A valve for flushing water closets comprising a casing, a water inlet passage, water outlet ports in the casing, a reciprocable valve interposed between the inlet and outlet ports, a rod for opening the valve, means 30 for closing the valve, timing means utilizing water from the inlet passage for timing the closing movement of the valve, and a distributing sleeve reciprocable with the rod having a successively circulating annular 40 and transverse port for controlling the flow of water through the outlet ports, whereby water may be directed through different channels during the closing movement of the valve.
4. A valve for flushing water closets comprising a casing, a water inlet passage, water outlet ports in the casing, a reciprocable valve interposed between the inlet and outlet ports having an annular transversely circulating port, a rod for opening the valve, means for closing the valve, timing means utilizing water from the inlet passage for timing the closing movement of the valve, a 50 distributing sleeve reciprocable with the rod for controlling the flow of water through the outlet ports, whereby water may be directed through different channels during the closing movement of the valve, and adjustable means for regulating the period of time required for closing the valve, whereby the 55 valve may be adjusted to the water pressure.
5. A valve for flushing water closets comprising a casing, a water inlet passage, water outlet ports in the casing, a reciprocable valve interposed between the inlet and outlet ports having a continuously annular port, a rod for opening the valve, means for closing the valve, timing means utilizing water from the inlet passage for timing the closing movement of the valve, a distributing sleeve reciprocable with the rod for controlling the flow of water through the outlet ports, whereby water may be directed through different channels during the closing movement of the valve, and adjustable means outside the casing for regulating the period of time required for closing the valve, whereby the valve may be adjusted to the water pressure.
6. A flushing valve for water closets comprising a casing, a gland at one end of the casing, an operating rod passing therethrough, outlet ports in the wall of the casing, a distributing valve for the ports loosely connected with a rod but movable therewith and having a continuously annular transversely circulating port, a water inlet for the casing, a valve for controlling the flow of water from the inlet to the outlet ports, said valve also being loosely connected with said rod, said loose connections enabling the parts to move with the rod and adjust themselves to irregularities within the casing without causing the parts to bind.
7. A flushing valve for water closets comprising a casing, an operating rod extending into the casing through the top thereof, outlet ports in the side of the casing, a sleeve valve connected with the rod having a continuously annular transversely circulating port for controlling the flow of water through the ports, a wafer inlet connection below the ports, and a main valve mechanism for controlling the flow of water from the inlet to the outlet ports, said mechanism including a valve body fitted in the casing having a sealing ring thereon and having a restricted passageway therethrough, a central passageway in the body through which an extension of the operating rod is passed, said body and rod having a lost motion connection between them whereby one may have a limited movement relatively to the other but are together during the greater portion of the travel of the rod, a by-pass valve in the central passageway secured to said rod, whereby it is seated and unseated by the lost motion between the said valve body and rod, said by-pass valve being opened upon operation of the rod to open said main valve to relieve the pressure of the water between said valve body and the bottom of the casing, and a spring for urging the various parts to normal closed position.

8. A flushing valve for water closets comprising a casing, an operating rod extending into the casing through the top thereof, outlet ports in the side of the casing, a sleeve valve connected with the rod having a continuously annular transversely circulating port for controlling the flow of water through the ports, a water inlet connection below the ports, and a main valve mechanism for controlling the flow of water from the inlet to the outlet ports, said mechanism including a valve body fitted in the casing having a sealing ring thereon and having a restricted passageway therethrough, a reciprocable pin in said restricted passageway for maintaining it free of foreign particles, a central passageway in the body through which an extension of the operating rod is passed, said body and rod having a lost motion connection between them, whereby one may have a limited movement relatively to the other but are together during the greater portion of the travel of the rod, a by-pass valve in the central passageway secured to said rod, whereby it is seated and unseated by the lost motion between the said valve body and rod, said by-pass valve being opened upon operation of the rod to open said main valve to relieve the pressure of the water between said valve body and the bottom of the casing, and a spring for urging the various parts to normal closed position.
9. A flushing valve for water closets comprising a casing having two spaced-apart outlet ports in the side walls thereof, a water inlet connection below the outlet ports, a reciprocable valve for controlling the flow of water through the casing, and a reciprocable distributing valve having a continuously annular port for directing the flow of water through the ports, and a common operating rod for effecting the simultaneous movement of both valves.
10. A flushing valve for water closets comprising a casing having two spaced-apart outlet ports in the side walls thereof, a water inlet connection below the outlet ports, a reciprocable valve for controlling the flow of water through the casing, a reciprocable distributing valve for directing the flow of water through the ports, said distributing valve comprising a sleeve through which water may flow from one end to the other and having a continuously annular port therethrough intermediate its ends, said port normally registering with one of the ports in the casing, the sleeve normally leaving the other port uncovered, said sleeve being arranged to uncover first one port and then the other, and then establish communication to both ports simultaneously, and a common operating rod for effecting the simultaneous movement of both valves.
11. A flushing valve for water closets comprising a substantially cylindrical casing having longitudinally extending integral ribs thereon, two spaced-apart annular ports in the wall of the casing, said ribs serving to hold the parts together, a sleeve valve in the casing for controlling the flow of water through the ports, and operating means for the sleeve valve.
12. A flushing valve for water closets comprising a substantially cylindrical casing having longitudinally extending integral ribs thereon, two spaced-apart annular ports in the wall of the casing, said ribs serving to hold the parts together, a sleeve valve in the casing for controlling the flow of water through the ports, said sleeve valve including a sleeve open at opposite ends and having ribs on the interior thereof, the sleeve having an annular port therein adapted to be moved into and out of register with one of the ports in the casing, said ribs serving to hold the parts of the sleeve together, and operating means for the sleeve valve.
13. A flushing valve for water closets comprising a substantially cylindrical casing having longitudinally extending integral ribs thereon, two spaced-apart annular ports in the wall of the casing, said ribs serving to hold the parts together, threads on the exterior of the ribs, a flanged nut threaded onto the ribs between the ports, a flange on the exterior of the casing below the ports, and a flanged member threaded on the casing above the ports, said nut, flange and flanged member being adapted to cooperate with a water closet for securing the casing in place, a sleeve valve in the casing for controlling the flow of water through the ports, and operating means for the sleeve valve.
- In testimony whereof I hereunto affix my signature.

THOMAS F. PAYNE.
